Attorney.

INVENTOR:

UNITED STATES PATENT OFFICE.

LOUIS C. GUENTHER, OF PROVIDENCE, RHODE ISLAND.

LEASE-ROD.

1,184,744.

Specification of Letters Patent. Patented May 30, 1916.

Application filed March 9, 1916. Serial No. 83,093.

To all whom it may concern:

Be it known that I, LOUIS C. GUENTHER, a citizen of the United States, residing at the city of Providence, in the county of 5 Providence and State of Rhode Island, have invented certain new and useful Improvements in Lease-Rods, of which the following is a specification.

My invention relates to an improved construction of lease-rod to form a warp-shed divider for weaving looms.

Heretofore, lease-rods constructed of enamel-coated metal tubes whose ends are plugged with wooden members, are objectionable, for the reason that the warp-threads cause innumerable fine grooves in the enamel surface, which, together with the shoulder left by the contiguous tube and wooden plug, frequently causes a breakage 20 of one or more of such threads when mounting the rod within the shed.

The object of my invention is to provide a grooved wooden filler extending the full length of the rod, and the latter wholly incased by a thin metallic member, to respectively retain its true shape and afford a minimum lightness to the rod; to maintain enduring wearing surfaces, and to render the rod to be quickly introduced between the 30 warp-threads without breakage of the same.

In the accompanying sheet of drawings, wherein like reference characters indicate like parts, Figure 1 is a plan view of my improved lease-rod; Fig. 2, a cross-section of 35 the latter; Fig. 3, a sectional edge view of the rod; Fig. 4, a plan sectional view of one of the end portions of the rod; Fig. 5, a cross-section taken on line $x-x$ of Fig. 3; Fig. 6, a plan view of a warp-shed, showing the application of two of my improved lease-rods 40 therein, and, Fig. 7, a section taken on line $y-y$ of Fig. 6.

In carrying out my invention my improved lease-rod (designated by reference 45 letter A as a whole,) has a filler member — a — which is preferably constructed from bass wood and extending the full length of the rod. The wooden member — a — is oval-shaped from end to end, and said member is 50 provided with a V-shaped groove formed throughout its length, in one edge thereof, as at — a^1 — in Fig. 2. The filler member — a — is wholly incased by a thin metallic

strip — b — whose opposed ends are inwardly bent to rest upon the faces of the groove 55 — a^1 —, in the manner shown at — b^1 , b^1 — in Fig. 2.

The metallic strip — b —, which forms a case for the rod, is secured upon the filler member — a — by a plunger and suitable 60 dies, and by means of which the top and bottom ends of the rod are made to curve slightly toward the extreme points of the same, as at — b^2 , b^2 — in Fig. 3.

In practice I find that bass wood, to form 65 a filler member for an article of this nature, gives the best results; as it affords a minimum lightness to the article; it has a close grain, and after being kiln-dried does not shrink or swell, and therefore retains its true 70 shape permanently.

After the filler member has been incased in the member — b — the end portions of the groove, left by the inturned edges of the latter member are filled with solder, as at 75 — c — in Figs. 4 and 5, in order to provide a smooth rounded finish at these points of the rod.

The case — b — is constructed from lead-coated thin soft steel, of 30 gage, and which 80 coated metal provides a perfectly smooth and durable wearing surface to receive warp-threads.

I manufacture the rod, as described, of different weights, for use according to the 85 size and number of warp-threads for weaving.

In use the rod is mounted in the shed with its rounded edge — b^2 — toward the whip-roll — d —, in the manner shown in Fig. 7, 90 and each rod is prevented from displacement by means of a cord — s — which is looped around the said roll and has its free portion attached in a perforation — n — formed through each end of the rod, as shown in 95 Fig. 6.

By my improved construction it is seen that I provide an article of this character possessing the advantage of having an ideal smooth and durable wearing 100 surface for warp-threads, thereby lessening friction of the latter, and at the same time the rod having no exposed joints or shoulders between its end points, renders the article to be quickly mounted without injury 105 or breakage of the threads.

What I claim and desire to secure by Letters Patent is,—

As an improved article of manufacture, a lease-rod consisting of an oval-shaped wooden filler member, a V-shaped groove formed along one longitudinal edge of said member, a thin lead-coated metallic strip surrounding the latter and having its opposed edges inturned against the faces of

the groove, and said strip forming a case 10 wholly inclosing the said filler member, substantially as set forth.

In testimony whereof I affix my signature in presence of two witnesses.

LOUIS C. GUENTHER.

Witnesses:

PATRICK A. CUNNINGHAM,
EDGAR E. HOBBS.
